ANIMATED DISPLAY

Donald L. Peterson, Minneapolis, Minn.

Application May 3, 1937, Serial No. 140,378

6 Claims. (Cl. 40—138)

This invention relates to animated display devices of a type particularly adaptable for use on street cars, busses and other moving vehicles.

Several types of animated display devices of this general type have been developed but they all have one major drawback, and that is an excessive cost of production. Take, for instance, the well known type of advertising known as "car cards," such as are used in street cars and busses. They are usually made of a piece of cardboard with advertising matter printed thereon. Advertising contracts for cards of this type are often of short duration and for that reason the cards must be of inexpensive structure. Furthermore, new forms of advertising are made up from time to time in advertising the same product.

In view of these facts, it is a general object of my invention to provide an animated display device which is inexpensive from an original construction standpoint and which can be quickly and cheaply transferred from one card to another.

Another object of the invention is to provide a construction which is effective in operation and which does not detract from the appearance of the card to which it is applied.

These and other and further objects and advantages of the invention will more fully appear from the following description made in connection with the accompanying drawing wherein like reference characters refer to the same or similar parts throughout the views, and, in which:—

Fig. 1 is a fragmentary front elevation of a car card with my invention shown in dotted lines;

Fig. 2 is an end elevation of a car card with my invention applied thereto;

Fig. 3 is a plan view of my improved construction;

Fig. 4 is a rear elevation thereof;

Fig. 5 is a section taken on the line 5—5 of Fig. 3; and

Fig. 6 is a plan view of the bracket plate shown attached to a portion of an advertising card.

In the drawing, I have illustrated an advertising card 7 which in this instance represents a car card such as is used on street cars and busses. Most of these cards are bent near their bottom edges as shown at 8, a shape which is customary in cards of this type. In the exemplary embodiment of my invention, there is indicated the head and shoulders of a woman who is supposed to be shampooing her hair. As shown, one hand is raised with the fingers thereof rubbing through

the hair and the soapsuds used for washing the hair.

To make the advertisement more striking to the eye, provision is made for causing movement of the hand of the woman relative to her head. Therefore, the hand 9 is printed upon a separate piece of cardboard and the like, and this element is cut out in the shape of a hand.

Secured to the back portion of the movable hand element 9, is an anchor plate 10, which has a substantially flat surface with an upstanding medial crimped portion 11, which is adapted to securely retain the end of a bar spring 12. This bar spring is preferably of a high grade of spring steel, such as is used in the better makes of watches. The anchor plate is provided with a plurality of spaced apertures 13 and the plate is secured to the movable card element 9 by passing wire staples 14 through the card and the apertures 13 and then bending over the ends of 20 the staples, as best shown in Fig. 4. It is preferred that the pairs of openings 13 be spaced apart a distance which will permit the use of an ordinary stapling machine, such as is commonly used for securing papers together. If desired, 25 the bar spring 12 may be soldered or spot welded within the crimped portion 11 of the anchor plate 10.

The opposite end of the bar spring 12 is connected to the base card 7 by means of a pair of 30 co-operating connector elements which form a quick detachable connection. Suitably positioned on the base card 7, is a bracket plate 15 which has spaced apertures 16 similar to the apertures 13 in the anchor plate 10 and wire staples 17 are 35 used to secure the bracket plate to the card. This plate is provided at its edges with stepped up portions 18 so that the edges are spaced slightly from the surface of the card to which the bracket plate is secured.

A box-like connector element B is provided with a substantially flat base portion 19 with its medial portion 20 crimped to secure the lower end of the bar spring 12 in the same manner as the crimped portion 11 of the anchor plate 10. This box-like connector element B is provided with laterally extending parallel side walls 21 which extend from the base 19 to a point beyond the extension of the medial crimped portion 20. Then the outer edges of the side portions 21 are 50 bent inwardly toward each other parallel to the base 19, to provide slide elements 22. Extending inwardly from the upper ends of the slide elements 22 are a pair of turned over stops 23 and the lower portions of the slide elements are 55

tapered off as at 24. Thus it will be seen that the box-like connector element B can be connected to the bracket plate 15 by slipping it over said plate with the slide elements 22 passing 5 downwardly behind the stepped edges 18 on the bracket plate 15, this sliding movement terminating when the stops 23 contact the upper edges 25 on the said stepped up portions 18.

In order to conceal the bar spring 12 and the 10 box-like connector element B, there is provided a cover card 26 which is secured to the flat face 19 of the box-like connector B by means of wire staples 27 which pass through the cover card and through spaced apertures 28 formed in the 15 flat side of the connector element B in the same manner as the staples described in connection with other parts of the device. It is preferred that the cover card 26 be colored or designed to blend in with that portion of the base card 7 20 over which it lies.

From the foregoing, it will be seen that with the elements secured in approximately the position shown in Fig. 1 the movable card element 9 representing the hand of the figure illustrated 25 on the card will oscillate back and forth with a movement which will simulate the action of a hand in shampooing the hair. Of course, for different types of displays, the movable element and the parts supporting the bar spring can be 30 placed in any appropriate position relative to the base card. The metallic elements which make up the operating mechanism and securing plates can be quickly removed from the base card and the movable card element by straightening the 35 bent over ends of the wire staples and removing the staples. Then these metallic elements can be quickly and easily applied to a different base card. Furthermore, the use of the small piece of cover card 26 effectively covers the box-like connector B and the bracket plate 15. This 40 permits the assembly of a movable element upon the front face of an advertising card without detracting from its appearance.

It will, of course, be understood that various 45 changes can be made in the form, details, arrangement and proportions of the various parts without departing from the scope of my invention.

What is claimed is:

50 1. In an animated display device, a base card element, a cooperating card element movable with respect to said base card element, a bar spring member, an anchor element, connected to one of said card elements and connected 55 to an end of said spring, a connector element secured to the opposite end of said spring, an attaching member secured to the other of said card elements and having a portion for detachably connecting with said connector element.

2. In an animated display device, a base card element, a cooperating movable card element, an anchor element secured to one of said card elements, a resilient spring, said anchor element having a portion rigidly engaging one end 5 of said spring, a bracket member secured to the other of said card elements and a connector having a portion rigidly engaging the opposite end of said spring, said bracket member and said connector including cooperating portions providing a quick detachable connection therebetween.

3. In an animated display device, a base card element, a cooperating movable element, an anchor plate having an aperture therein, a 15 clincher element extending through one of said card elements and through the aperture in said anchor plate to rigidly connect said card element and said anchor plate, a bracket plate having an aperture therein, a clincher element, extending through the other of said card elements and the aperture in said bracket plate to rigidly secure said bracket plate to said card element, and a resilient element connected between said bracket plate and said anchor plate. 20

4. The structure in claim 3, and said anchor plate and said bracket plate having spaced apertures therein, and said clincher elements comprising wire staples extending through said card elements and the apertures in said anchor plate 30 and bracket plate.

5. In an animated display device, a base card element, a cooperating card element movable with respect to said base card, said movable card element being designed to simulate motion of a portion of said base card, an anchor plate, clincher elements connecting one of said card elements and said anchor plates, a connector element comprising a box-like structure having a flat base portion and a medial upstanding crimped portion, parallel side portions extending upwardly from said base portion, slide elements on said side portions and spaced from said base portion, a bracket plate, clincher elements securing said bracket plate to the other of said card elements, said slide elements being adapted to slide beneath portions of said bracket plate between said bracket plate and said card element to secure said box-like connector to said bracket plate, a crimped portion on said anchor plate, and a bar spring whose ends are rigidly secured in the crimped portions of said anchor plate and said box-like connector. 40 45

6. The structure set forth in claim 5 and a cover card element superposed upon said box-like connector to conceal it from view. 50 55

DONALD L. PETERSON.
